UNITED STATES PATENT OFFICE.

EDWARD GERMAIN, OF SAGINAW, MICHIGAN.

DESIGN FOR A MANTEL.

SPECIFICATION forming part of Design No. 21,155, dated November 10, 1891.

Application filed October 14, 1891. Serial No. 408,723. Term of patent 7 years.

To all whom it may concern:

Be it known that I, EDWARD GERMAIN, of Saginaw, in the State of Michigan, have invented and produced a new and original Design for Mantels, of which the following is a specification.

The accompanying drawings represent in Figure 1 a front elevation of the mantel, and in Fig. 2 a vertical central cross-section of the same with a view to better show the outline of the mantel.

The mantel has, as usual, pilasters *a*, plinths *b*, caps *c*, a frieze *d*, mantel-board *e*, grounds *f*, and fire-strips *g*.

The characteristic feature of my design resides more particularly in the configuration and ornamentation of the frieze and of the caps in connection with their pilasters. The caps have intagliated rosettes *h*, and at the junction of the caps with the pilasters are moldings *i* of the shape shown. Upon the frieze is a raised panel *j*, extending between the caps and having beveled edges *k* and

reeds *l*. The pilasters have beveled edges *m* and grooves or sunken lines *n*, which define the boundary between the plinths and the pilasters.

The mantel-board has a molded edge *o*.

p is the filling-strip along the upper part of the frieze.

r is a molding along the upper edges of the filling-strip and the caps.

s is a molding at the lower edge of the frieze.

The lower edge itself of the frieze is straight and without bevel.

What I claim, and desire to secure by Letters Patent, is—

The design for a mantel, as herein described and shown.

In testimony whereof I affix my signature in presence of two witnesses.

EDWARD GERMAIN.
